STORM SASH CONSTRUCTION

George J. Shink, Detroit, Mich., assignor of one-half to W. H. Bogart, Mount Clemens, Mich.

Application September 22, 1950, Serial No. 186,265

4 Claims. (Cl. 189—75)

1
This invention relates to a storm sash construction and more particularly to a frame for supporting a removable storm window panel.

It is an object of this invention to provide a storm sash construction which is economical and which is adapted for use with various types of window constructions and particularly with metal casement windows.

A further object of the invention resides in the provision of a channel section of particular configuration which is admirably suited for making frames for removably supporting storm sash panels.

Another object of the invention is to provide a frame member which is adapted to be insulatively mounted on a window frame and retain a screen on one side thereof and a removable storm sash panel on the other side thereof.

A still further object of the invention resides in the provision of a simple but very rigid corner construction for a frame for a removable storm sash panel.

In the drawings:

Fig. 1 is a front elevation of the storm sash construction of this invention and a casement window associated therewith.

Fig. 2 is a sectional view taken along the lines 2—2 in Fig. 1.

Fig. 3 is a sectional view taken along the lines 3—3 in Fig. 1.

Fig. 4 is a fragmentary sectional view taken along the lines 4—4 in Fig. 1.

Fig. 5 is a sectional view similar to Fig. 2 and showing the manner in which the removable storm sash panel may be inserted into or removed from the frame associated therewith.

Fig. 6 is a fragmentary perspective view, partly in section, of the storm sash construction as applied to another type of window.

Fig. 7 is a fragmentary perspective view of the corner construction of the frame for the removable storm sash panel.

Fig. 8 is a cross section of the channel stock from which the frame is constructed.

Referring to the drawings, the storm sash construction of this invention is illustrated in connection with a metal casement window which generally comprises a frame 10 and a glazed sash 12 which is adapted to fit into and close the opening defined by frame 10. Along one vertical edge sash 12 is pivotally supported on frame 10 by hinge members 14. Hinges 14 are of conventional construction and comprise a pair of bushings 16 and 18 which are secured together for relative rotation by a bolt 20. Bushings 16 and

2
18 are spaced outwardly from the front face of frame 10, bushing 16 being rigidly connected with the front face of sash 12 by a hinge bracket 22 and bushing 18 being rigidly connected with the front face of frame 10 by a hinge bracket 24. In a window of this type the sash usually opens by swinging outwardly on hinges 14, and for this reason a storm sash is usually mounted on the outer face of sash 12.

The storm sash of this invention comprises a rectangular frame 26 and a removable sash panel 28. Panel 28 comprises a rectangular frame 30 of channel-shaped cross section in which is retained a sheet of glass 32. The frame 26 comprises side rails 34 and 36 and top and bottom rails 38 and 40, respectively. These rails all have the same cross section and are preferably formed from an extruded channel section, the cross section of which is shown in Figs. 7 and 8. The channel section from which these rails are formed is preferably extruded in the form of two integrally connected channel sections 42 and 44. Channel section 44 has side walls 46 and 48 and a top wall 50. Channel section 42 has a side wall 52 and a side wall 54 which is formed as an extension of side wall 46 and by means of which the two channel sections are integrally connected with the top wall 50 of channel section 44 spaced below and offset transversely of the top wall 56 of channel section 42. Along its lower longitudinal edge, side wall 52 is fashioned with a flange 58 which extends outwardly substantially perpendicular to the plane of side wall 52 and in a direction away from channel section 44. On the inner faces of side walls 52 and 54 there are formed opposed longitudinally extending beads 60.

The frame 26 is fashioned from the stock illustrated in Fig. 8 by cutting the rails 34, 36, 38 and 40 therefrom and mitering the ends thereof so that the rails may be arranged into the rectangular frame illustrated. The ends of the rails are mitered such that the flange 58 defines the inner peripheral edge of frame 26 and the side walls 48 of channel sections 44 define the outer peripheral edge of the frame. These rails are locked together at the mitered corners thereof by a one piece corner bracket 62 having perpendicularly arranged leg portions which are arranged to snugly slide into the channel sections 42 of the adjacent rails. The brackets 62 have a thickness corresponding to the distance between the inner face of top wall 56 of channel section 42 and the beads 60. After the rails are assembled with the corner brackets in the man-

ner illustrated in Fig. 7, the rails are locked together by striking the beads 60 with a sharp tool such as a pointed punch so as to deform a portion of the beads and a corresponding portion of brackets 62. These deformed portions or punch marks are indicated at 64. I have found that a frame fashioned from the stock illustrated in Fig. 8 and constructed in the manner shown in Fig. 7 is not only very rigid but readily assembled.

The frame 26 is secured to the outer face of sash 12 by screws 66 which are driven through the top wall 50 of channel sections 44 and threaded into suitable holes formed on the front face of sash 12. In order to obtain a tight and weatherproof fit between frame 26 and the outer face of sash 12, a filler strip 67 preferably formed of rubber is inserted in channel sections 44, the filler strip 67 being greater in depth than channel sections 44 so that it is compressed to fit snugly against the outer face of sash 12 when the screws 66 are tightened.

One of the difficulties usually encountered in fitting a storm window to the outer face of a casement sash of the type illustrated in Fig. 1 arises from the fact that the hinges 14 and the brackets 22 which connect the sash 12 with the hinge form obstructions which necessitate cutting away a portion of the storm sash frame at the upper and lower corners at one side thereof. The storm sash of this invention is designed especially to take care of this problem. In conventional constructions, when the corners of the frame are cut away to accommodate the hinges and the hinge brackets on the casement sash, portions of the means for connecting the rails at the corners of the frame are also removed. In my storm sash construction this objectionable feature is eliminated. It will be noted that the rails of the frame are connected together at the corners by the brackets 62 and that these brackets are disposed within channel sections 42 which are spaced inwardly of channel sections 44 on the frame. Therefore, in order to accommodate the hinges 14 and hinge brackets 22, channel sections 44 may be cut away, as at 68, and the corner locking means which comprise the brackets 62 and the channel sections 42 remain intact.

The upper face of flange 58 and the outer face of side wall 52 of channel sections 42 define a seat for the frame 38 of panel 28. Panel 28 is arranged to be removably retained within the seat formed by flange 58 and side wall 52 by brackets 70 and 72. These brackets are secured to upper and lower rails 38 and 40 and overlie the upper and lower edges of the opening defined by the outer face of side walls 52. The upper bracket 70 overlies this opening a greater extent than the lower bracket 72, and panel 28 is shorter in height than the height of the opening so that it may be inserted in the opening in slightly tilted position to engage the upper end of the panel behind bracket 70 as is clearly shown in Fig. 5. Panel 28 can then be pushed upwardly to a position where the lower edge of the panel clears the edge of bracket 72 whereupon the lower end of the panel can be pivoted inwardly and the panel dropped slightly so that its lower edge rests upon the side walls 52 of bottom rail 40 and the upper edge of the frame is engaged behind bracket 70.

In the type of window illustrated in Fig. 1 a second frame 74, which is constructed substantially the same as frame 26, may be secured to the window frame 10 on the inner face of the window.

In this instance the channel sections 42 may be employed for receiving rods or pins 76 which secure the ends of a screen 78 in channel sections 42. The frame 74 thus secured to the inner face

5 of the window frame may be provided with the removable storm sash panel, if desired. The frame 74 may also be used on the outer face of casement window frames in which the window opens inwardly such as is illustrated in Fig. 6. 10 In this arrangement the frame 74 is provided with a screen 78 and may be secured directly to the outer face of the frame 80. Brackets 82, which are similar in function to brackets 70 and 72, may be employed for retaining the storm sash panel 15 84 within frame 74.

It will thus be seen that I have provided a storm sash construction which is economical, rigid and admirably suited for use with casement windows. Furthermore, as described above, the 20 storm sash arrangement of this invention may be applied either to the inner face or the outer face of a casement window. The particular frame construction described herein enables fitting the frame around the hinge members for the window without weakening the corner construction of the frame. At the same time, the frame is designed to retain either a removable storm sash panel or a screen or both a screen and sash panel simultaneously.

30 I claim:

1. A combined window support, insulation retainer and locking channel member comprising a pair of inverted, U-shaped channel sections integrally connected by a common side wall and 35 extending longitudinally side by side, said channel sections being similarly disposed with the lower open face of one section lying in a plane spaced below the plane of the lower open face of the other channel section, said last mentioned channel section having a longitudinally extending flange along the outer face of the side wall thereof which is remote from said other channel section, said flange being disposed adjacent the lower free edge of said side wall and extending in a plane generally perpendicular to the plane of said side wall, said channel section provided with said flange having a pair of opposed longitudinally extending beads on the inner faces of its side walls and said other channel section having apertures 40 in the top wall thereof to receive fastening members.

2. A combined window support, insulation retainer and locking channel member comprising a first channel section having a pair of spaced apart side walls and a top wall connecting said side walls along corresponding longitudinal top edges thereof, a second channel section integral with said first section and having a pair of spaced apart side walls and a top wall connecting said last mentioned side walls, said channel sections being disposed with the top walls of said sections spaced vertically and offset in a direction transversely of said channel sections, the channel section with the lower top wall having the lower ends of its side walls disposed in a plane below the lower ends of the side walls of the other channel section and having one of its side walls extending as a continuation of a side wall of the other channel section, the other side wall of said last mentioned channel section having a longitudinal flange extending therefrom in a plane perpendicular to the plane of the last mentioned side wall, said channel section provided with said flange having a pair of opposed longitudinally extending beads on the inner faces of its side walls and said other chan-

nel section having apertures in the top wall thereof to receive fastening members.

3. The combination set forth in claim 2 wherein said flange is disposed generally at the level of the lower top wall.

4. A frame for attaching a storm window to a window to be insulated comprising a pair of side rails and a pair of end rails, said rails all having the same cross section and each comprising two longitudinally extending and integrally connected channel sections, said channel sections being disposed side by side and being offset vertically, said channel sections being open at the bottom face thereof, the upper channel section having a flange adjacent the lower edge of its side wall remote from the other channel section, said flange extending generally perpendicular to the last mentioned side wall in a direction away from the other side wall of said upper channel section, said rails being mitered at the opposite ends thereof and arranged into a rectangular frame having mitered corners, said flange forming the inner peripheral edge of said frame and providing a stop against which a window panel may be positioned when in-

serted within the opening defined by the last mentioned side walls of each of said rails, said upper channels having a pair of opposed beads extending longitudinally on the inner faces of the side walls thereof, said lower channels having apertures in the top walls thereof to receive fastening means for attaching said frame in place around a window opening and means disposed within the upper channels at each of said mitered corners for locking said rails together.
